(57) **CLAIM**

The ornamental design for a wound dressing, as shown and described.

DESCRIPTION

FIG. 1 is an isometric view of one embodiment of a wound dressing.

FIG. 2 a top side view of the wound dressing illustrated in FIG. 1.

FIG. 3 is a bottom side view of the wound dressing illustrated in FIG. 1.

FIG. 4 is a front side view of the wound dressing illustrated in FIG. 1.

FIG. 5 is a back side view of the wound dressing illustrated in FIG. 1; and,

FIG. 6 is a left side view of the wound dressing illustrated in FIG. 1, where a right side view is not illustrated as it is a mirror image of the left side view.

In FIGS. 1 and 3-6 the broken lines illustrating an edge thickness of the wound dressing and a bottom layer of the wound dressing depict environmental subject matter only and form no part of the claimed design.

In FIGS. 1-2 and 4-6 the broken lines illustrating an absorbent pad of the wound dressing depict environmental subject matter only and form no part of the claimed design.
